(57) **CLAIM**

The ornamental design for an ultrasound probe as shown and described.

DESCRIPTION

FIG. 1 is a top-rear-left perspective view of an ultrasound probe showing our new design;

FIG. 2 is a left side view of the ultrasound probe of FIG. 1. FIG. 3 is a right side view of the ultrasound probe of FIG. 1.

FIG. 4 is a front view of the ultrasound probe of FIG. 1. FIG. 5 is a rear view of the ultrasound probe of FIG. 1. FIG. 6 is a top view of the ultrasound probe of FIG. 1; and, FIG. 7 is a bottom view of the ultrasound probe of FIG. 1. The dash-dash broken lines in the drawings illustrate portions of the ultrasound probe that form no part of the claimed design.
